Attorneys

UNITED STATES PATENT OFFICE.

LONNIE M. MOORE, OF HOPKINSVILLE, KENTUCKY, ASSIGNEE OF ONE-HALF TO
C. HEWLETT JACKSON, OF HOPKINSVILLE, KENTUCKY.

COMBINED CURTAIN ROD AND SHADE BRACKET.

Application filed May 29, 1922. Serial No. 564,320.

To all whom it may concern:

Be it known that I, LONNIE M. MOORE, a citizen of the United States, residing at Hopkinsville, in the county of Christian 5 and State of Kentucky, have invented certain new and useful Improvements in Combined Curtain Rods and Shade Brackets, of which the following is a specification.

This invention relates to curtain rod fixtures and more particularly to that class which are adjustable to window frames and shades of varying dimensions.

The primary object of the invention is the provision of a bracket which can be readily 15 secured in position upon a window curtain rod without necessitating the use of permanent fastening means, thereby rendering the bracket adjustable to varying conditions and dimensions of shade rollers.

Another object is the provision of a 20 bracket which is extremely simple in construction, strong, efficient in its purpose and which does not interfere with the draperies supported by the curtain rod.

The invention consists in the features of 25 construction and arrangement of parts described and illustrated in the accompanying drawings.

In the drawings, Figure 1 is a vertical 30 front view of a window frame showing an adjustable curtain rod secured thereto with two brackets in position upon the rod;

Figure 2 is a rear vertical view of the curtain rod with the brackets attached;

Figure 3 is a vertical sectional view of the 35 bracket taken upon line 3—3 of the bracket and rod shown in Figure 2; and

Figure 4 is a vertical sectional view of the bracket and represents the manner in 40 which the same is applied and disengaged from the curtain rod.

Referring to the drawings in detail, 1 designates a window frame upon which is fastened an adjustable curtain rod comprising 45 two grooved or channeled sections, 2 and 3, slidable one within the other and maintained upon the frame by means of spurs 4 which dig into the wood under the pull of a spring 5, which is positioned in the groove 50 of the sections 2 and 3 and has its opposite ends connected to the two sections 2 and 3 by means of hooks 6 which are struck up from the two sections on the groove side thereof and extend in opposite directions. 55 Extending longitudinally along the rod at

either end portion is a series of holes 7 spaced with respect to each other, and extending through the rod body. The purpose of these holes will be described at some other point of this description. 60

As shown in Figure 3, the shade bracket is composed of two resiliently yieldable plates 8 and 9, so connected at one portion thereof to form a device which straddles the rod section. The base plate 8 is so situated as to resiliently and yieldably engage the inner face of the rod and on the lower portion thereof is fastened the well known form of roller supporting member 11. From the intermediate portion of base plate 8, a protruding member 12 extends beneath the lower marginal edge 15 of the curtain rod, the purpose of this member being to prevent any rotational movement of the bracket with respect to the rod. One particular form that this protruding member may assume may be that of a lip struck up from the base plate and bent so as to extend beneath the rod. Secured to the upper end portion of base plate 8 is another resiliently yieldable plate 70 9 which is so constructed as to be in contact with base plate 8 for a portion of its length and is then bent so as to conform to the rod 2. Thereupon the plate 9 extends downwardly and yieldably engages the outer face 85 of the curtain rod. The lower extremity of plate 9 is then bent as shown at 10, this bent portion yieldably engaging the protruding member 12. Pins 14 are placed on the inner face of plate 9 adjacent the curtain rod and are adapted to engage the openings 7 for the purpose of securing the bracket to the curtain rod and preventing any movement of the same along the rod. These pins also serve to prevent any rotational movement of 90 the bracket with respect to the rod. To initially adjust the bracket upon the rod, the plates 8 and 9 are spread apart, plate 8 being placed behind the rod and plate 9 in front of the rod as shown in Figure 4. Since 100 both plates are connected at 13, they straddle the rod and for final adjustment the bracket is pressed downward into place thus causing the plates to yieldingly engage the respective faces of the rod. To adjust the brackets so as to accommodate any length of shade roller, they are moved along the rod by spreading the plate members 8 and 9 thereby disengaging pins 14 from the holes. When the required spacing has been ob- 110

tained, the plates are allowed to snap together, thereby causing the pins to engage the proper holes and secure the brackets to the curtain rod.

5. This type of bracket is readily adjustable to any supporting means or upon rods having flat engaging surfaces, and particularly upon rods having a series of openings along their length.

10. I claim:—

1. In a curtain fixture the combination of a rod having a series of holes therethrough with a shade roller bracket, said bracket comprising a base plate yieldingly engaging

15 one face of said rod, said base plate having a protruding member struck up therefrom and adapted to project beneath the lower marginal edge of said rod, a roller supporting element disposed on the lower end portion

20 of said base plate, a spring plate having one end fixed to the upper end portion of said base plate and adapted to yieldingly engage the face of said rod opposite to that engaged by the base plate, the opposite end

25 portion of said spring plate being bent towards said base plate to yieldingly engage said protruding member and having on the face next adjacent said rod a pin projecting toward the base plate and adapted to enter

30 one of the holes.

2. In a curtain fixture, the combination of a rod having a series of holes therethrough with a shade roller bracket, said bracket comprising a base plate slidably associated

35 with said rod and having an intermediate upstruck transverse rib; a roller supporting element disposed on the lower end portion of said base plate, a resilient member secured for a portion of its length to the upper end

40 portion of said base plate and in spaced relation to said base plate for the remaining portion of its length, said member straddling said rod and slidably associated with the outer face of said rod, the free end of

45 said resilient member being bent to engage said upstruck rib and a pin on said resilient member to engage and be disengageable from the holes on said rod.

3. In a curtain fixture the combination of a rod with a shade roller bracket, said bracket comprising a base plate yieldingly engaging one face of said rod, said base plate having a protruding member struck up therefrom and adapted to project beneath

55 the lower marginal edge of said rod member, a roller supporting element disposed on the lower end portion of said base plate, and beneath said protruding member and extending in the same direction therewith, a

60 spring plate having one end fixed to the upper end portion of said base plate and

adapted to yieldingly engage the face of said rod opposite to that engaged by the base plate, and locking means for securing the bracket in any predetermined position along the length of the rod.

4. In a curtain fixture, the combination of a supporting member with a shade roller bracket, said bracket comprising a base plate yieldingly engaging one face of said supporting member, said base plate having a protruding member struck up therefrom and adapted to project beneath the lower marginal edge of said supporting member, a roller supporting element disposed on the lower end portion of said base plate, and beneath said protruding member and extending in the same direction therewith, a spring plate having one end fixed to the upper end portion of said base plate and adapted to yieldingly engage the face of said supporting member opposite to that engaged by the base plate.

5. In a curtain fixture the combination of a supporting member with a shade roller bracket, said bracket comprising a base plate yieldingly engaging one face of said supporting member, a roller supporting element disposed on the lower end portion of said base plate, a spring plate secured to the upper end portion of said base plate and having a portion projecting downward in yieldable spaced relation to said base plate, both said roller supporting element and said spring plate projecting from the same side 95 of said base plate, and locking means for securing the bracket in any predetermined position along the length of the rod.

6. In a curtain fixture the combination of a rod with a shade roller bracket, said bracket comprising a base plate yieldingly engaging one face of said rod, protruding means on said base plate projecting beneath the lower marginal edge of said rod to prevent a rotational movement of said bracket 100 with respect to the rod, a roller supporting element disposed on the lower end portion of said base plate, and beneath said protruding means and extending in the same direction therewith, a spring plate having 110 one end fixed to the upper end portion of said base plate and adapted to yieldingly engage the face of said rod opposite to that engaged by the base plate, both said roller supporting element and said spring plate projecting from the same side of said base plate, and locking means for securing the bracket in any predetermined position along 115 the length of the rod.

In testimony whereof I affix my signature.

LONNIE M. MOORE.
